UNITED STATES PATENT OFFICE.

THOMAS M. JONES, OF GARDEN CITY, KANSAS.

DITCH CHECK.

Application filed February 21, 1927. Serial No. 169,944.

This invention relates to a check designed for use in connection with irrigating ditches. Various means have been devised heretofore for checking the water in ditches at desired points. Among these have been gates having their ends embedded in the sides of the ditch and upstanding side members having gates mounted therein in different ways. The means heretofore employed have been objectionable, however, because of the flow of the water over and against the checks or gates has tended to wash away the soil at the bottoms and sides of the checks with the result that it has been difficult and almost impossible to retain the water at the points where the checks are located. The means thus far employed for holding the water in check have also been objectionable because, when machines have been moved along the ditches for the purpose of cleaning them out, they have frequently dislodged the checks, thereby necessitating the expenditure of considerable time and labor in resetting the parts.

It is an object of the present invention to provide a check which can be permanently set across a ditch and will not permit undesirable leakage of water.

A further object is to provide a check which will not interfere with the proper movement of a machine along the ditch used for cleaning out the ditch, the parts of the check being arranged at such angles as to deflect any portions of the machine that might come into contact therewith and prevent them from becoming caught on the check.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred forms of the invention have been shown.

In said drawings,

Figure 1 is a plan view of a portion of an irrigating ditch having arranged thereacross a check such as constitutes the present invention.

Figure 2 is a section on line 2—2, Figure 1.

Figure 3 is a section on line 3—3, Figure 1.

Figure 4 is a transverse section through a slightly modified form of check.

Figure 5 is a perspective view of the modified form of check, the sections thereof being shown separated.

Referring to the figures by characters of reference A designates an irrigating ditch produced in the usual way and at any desired point or points a check such as constitutes the present invention is placed in position. In the form illustrated in Figures 1 to 3 inclusive the check is molded in a single piece of concrete and includes a base slab 1 and upwardly diverging side slabs 2, these slabs all being integral. The base slab 70 is arranged with its upper surface below the level of the bottom of the ditch as will be seen by referring particularly to Figure 2. The sides of the check are inclined at substantially the same angle as the sides of the ditch and the upwardly extending edges of each side panel 2 converge as shown at 3. The front or water receiving side of the check constitutes an abutment for the end portion of superposed slats 4 constituting the gate 80 portion of the check, these slats being supported in an inclined plane as shown so that no special fastening means are required in order to hold them in position inasmuch as the slats are held pressed against the sides 85 of the check by water pressure. These slats can be of wood, metal, or any other suitable material. In practice it is intended to mold the check in one piece by arranging a suitable form transversely of the ditch in proper 90 position relative to bottom and side recesses formed in the ditch. The concrete is then poured into the mold and when set will provide a complete one-piece check extending along the bottom and up the sides of the 95 ditch. If preferred, however, the check can be made of slabs which are separate. This modified arrangement has been illustrated in Figures 4 and 5 wherein the bottom slab is molded in one piece as shown at 5 while the 100 side slabs are in separate pieces as shown at 6. When these slabs are assembled the bottom slab is arranged between and abuts against the lower edges of the side slabs as shown in Figure 4. In other respects, however, the check constituting this modified structure is the same as the one heretofore described.

In practice the checks are arranged at desired distances apart along the irrigating 110

ditch and when the water is directed into the ditch from the main or supply ditch it will come against the gate 4 erected at the first check. Outlets are of course provided 5 in the ditch so that the water thus checked will flow laterally onto the land to be irrigated. Thereafter one or more of the slats 10 4 can be removed so that a portion of the water will be free to flow over the gate 4 and continue along the ditch to the gate at the next check. Thus irrigation of a second 15 section of the land can begin prior to the completion of the irrigation of the first section. Following this operation the remainder 20 of the first gate can be removed and the second gate can be built up to full height until irrigation of the second section of the land has been partially completed whereupon 25 the operation already described is repeated.

20 By providing the concrete bottom for the check, the water pouring over the gate will come in contact therewith and then flow gently off of the bottom slab into the ditch. Thus there is no danger of the bottom of the ditch 25 being worn away by the flow of water where it pours onto the check. Instead all of the erosion will be cared for by the check and the ditch will remain intact. Furthermore, 30 as the ends of the gate bear against the side panels there is no danger of the water working around said ends and into the check and thus leaking past the gate.

As has already been pointed out the checks

can be molded at the points where they are to be used or, if preferred, where a sectional check is used the different panels can be molded where sand and other materials are available and can thereafter be conveyed to the points of use and quickly set up. 35

While it is intended generally to form the 40 check of concrete molded to proper form, it is to be understood that any other suitable materials can be used provided they meet the requirements.

45 What is claimed is:

A check for irrigating ditches including 50 molded sides having upwardly converging edges, said sides diverging upwardly to conform substantially to the slope of the sides of the ditch, a molded bottom extending throughout the width of the ditch and throughout the width of the bottom portions of the sides, and a gate formed of separate superposed sections extending transversely 55 of the structure and adapted to be supported by the bottom of the ditch and to be maintained by gravity against the up-stream side edges of the sides of the check, the upper edge of the gate overhanging the bottom of the check thereby to direct onto said bottom all 60 water flowing over the gate.

In testimony that I claim the foregoing as my own, I have hereto affixed my signature.

THOMAS M. JONES
